UNITED STATES PATENT OFFICE.

MILTON J. MANN, OF BANGOR, PENNSYLVANIA.

CAN OPENER.

1,411,858.

Specification of Letters Patent. Patented Apr. 4, 1922.

Application filed January 6, 1920. Serial No. 349,753.

To all whom it may concern:

Be it known that I, MILTON J. MANN, a citizen of the United States, residing at Bangor, in the county of Northampton and State of Pennsylvania, have invented certain new and useful Improvements in Can Openers, of which the following is a specification.

This invention relates to can openers and has for its primary object to provide a device of this character in which the cutting element is adjustably associated with the handle so that cans of various sizes may be opened by the same tool; novel means being provided on the end of the handle for slidably engaging the rim of the can to be opened, whereby the cutting of the can-top may be more effectively and simply accomplished.

A further object of the invention is to provide a device of this character in which the parts are few and separable so that the replacement of broken or worn out parts may be easily effected by the unscrewing of the fastening means holding the injured or broken parts and the substitution of the duplicate parts.

With these and other objects, my invention consists in the details of construction and combination of parts as will be herein-after more fully pointed out and described, reference being had to the accompanying drawing, in which—

Figure 1 is a view of the can opener in side elevation illustrating the manner in which it is applied to a can, a fragmentary view of the latter being shown;

Figure 2 is a bottom plan view;

Figure 3 is a vertical longitudinal section and Figure 4 is a cross section taken on the line 4—4 of Figure 3.

The handle of the can opener may be of any desirable shape and size but for purposes of convenience the drawings illustrate the handle 1 as being a substantially flat, elongated body, squared at one end, as indicated at 2 while the other end is formed into a hand hold knob 3 having a reduced neck portion 4. The handle 1 is further provided with a narrow slot 5 extending lengthwise between the handhold and the squared end 2 and preferably centered between the side edges of the handle.

The cutting element of the device consists of a main plate 6 having side portions bent upwardly to provide flanges 7 and 8 respec-

tively. A knife blade 9 is associated with the plate 6 and depends downwardly from one end of the latter, as clearly illustrated in the drawing. The blade 9 and plate 6 may, if preferred, be made in one piece, or if found more practicable, the plate 6 may be formed of some cheaper grade steel, or other material and the knife 9 riveted or otherwise affixed thereto. The blade 9 is made concavo-convex so as to puncture the can top in arcs of a circle during the raising and lowering of the handle 1. The side cutting edges 10 converge to form a penetrating point 11 at the lowermost extremity of the blade 9 so that can tops of more than usual thickness may be readily penetrated by the cutting blade 9. The cutting blade is adapted to be adjustable along handle 1 with the plate 6 straddling the under face of the handle and crossing slot 5; the side flanges 7 and 8 of the plate embracing the handle along its side edges and providing guide means for the cutting knife during its adjustment longitudinally of the handle 1 but preventing any sidewise movement of the blade. A securing bolt 12 is inserted through plate 6 with its threaded shank extending up through the slot 5 for engagement with a thumb nut 13 which, upon being screwed up upon the bolt securely holds the cutting element in rigid engagement with the handle 1.

To provide a fulcrum at the squared end 2 of the handle, a support or can gripping member 14 is provided and consists of an elongated strip of metal or other suitable material disposed transversely of the handle end 2, and affixed to the handle by means of screws or other suitable fastening elements 15. The opposite ends of strip 14 are bent downwardly to provide spaced apart legs 16 each of which has a V-shaped notch 17 cut into the lower edge thereof. The notches 17 are adapted to fit over and engage the rim of the can at points offset from the longitudinal axis of the handle, as illustrated by Figure 2 and the legs 16 thus constitute a guiding element for the cutting knife.

Should either the blade 9 or the can gripping member 13 become worn out or broken, it is evident that they can be readily replaced by duplicate parts merely by the removal of the screws or other fastening means by which they are affixed to the handle 1.

In the operation of the implement when

it is desired to cut open a can top, the blade 9 is first adjusted concentric to the edge or rim of the can, whereupon the guide 14 engages the rim. By pressing downwardly on the handle, the said guide acting as a fulcrum, the knife penetrates the top and by simply holding the implement stationary and rotating the can, or by gripping the handle 3 between the blade and the guide, 10 a dragging movement of the handle will effect the cutting operation, since the said guide will maintain the implement in cutting position adjacent the said rim. Of course, when small sized cans are to be 15 opened, the implement may be seized by the hand at point substantially intermediate the ends of the handle and the can twisted to effect a proper cutting thereof.

Although the foregoing description and 20 accompanying drawings may be considered as referring to the preferred or approved form of the invention, it is to be understood that such changes in the construction, combination and arrangement of parts, etc., are 25 permissible, as may prove expedient and fall within the scope of the appended claims.

Having thus described my invention, what I claim as new and desire to secure by Letters Patent is:—

30 1. A can opener comprising a handle, guiding means at one end of the handle for slidably engaging the rim of a can and adapted to act as an initial fulcrum, and a can top penetrating cutter carried by the 35 handle.

2. A can opener comprising a handle, guiding means offset from the longitudinal axis of the handle for slidably engaging the rim of a can, a can top penetrating cutter 40 carried by said handle, said guiding means acting as an initial fulcrum for the cutter.

3. A can top opener comprising a handle, notched guiding means adapted to act as a fulcrum and disposed at one end of the 45 handle for slidably engaging the rim of a

can, and a can top cutter adjustable concentric to the said guiding means.

4. A can opener including a handle having a slot therein, a hand-hold adjacent one end of the slot, guiding means adjacent the other end of the slot for slidably engaging the edge of the can to be opened and adapted to act as an initial fulcrum, a curved knife depending downwardly from said handle and beneath said slot, and means 55 extending through said slot and adjustably supporting said knife.

5. A can opener including a handle, an arcuate knife carried by said handle and a guiding member depending from the under 60 side of said handle and notched for slid- able engagement with the rim of the can to be opened.

6. A can opener comprising a handle, a cutting member carried thereby, a guiding 65 element secured at one end of the handle for slidably engaging the rim of a can, said ele- ment comprising a strip having its ends bent downwardly in spaced relation from each other and notched to ride over the rim dur- 70 ing the cutting operation, said element also constituting an initial fulcrum for the said cutting member.

7. A can opener comprising a handle, hav- 75 ing a notched guiding element at one end and hand gripping means at the other end, a plate slidable along the under side of said handle, means for adjustably securing said plate to said handle, guide flanges project- 80 ing upwardly from said plate on opposite sides of said handle, and a knife blade de- pending from said plate in a direction oppo- site to said flanges.

In testimony whereof I affix my signature in presence of two witnesses.

MILTON J. MANN.
